AUTOMOBILE DOOR LATCH FLANGING TOOL

Virgil O. Lane, Arcadia, Calif.

Application May 24, 1948, Serial No. 146,550

Term of patent 7 years

(Cl. D54—13)

To all whom it may concern:

Be it known that I, Virgil O. Lane, a citizen of the United States, residing at Arcadia, in the county of Los Angeles and State of California, have invented a new, original, and ornamental Design for an Automobile Door Latch Flanging Tool, of which the following is a specification, reference being had to the accompanying drawing, forming part thereof.

Figure 1 is a perspective view of an automobile door latch flanging tool, showing my new design.

Figure 2 is a side elevation of the automobile door latch flanging tool of Figure 1.

Figure 3 is a top plan view of the tool.

Figure 4 is a view in end elevation, as viewed from the right in Figure 3.

I claim:

The ornamental design for an automobile door latch flanging tool, substantially as shown.

VIRGIL O. LANE.
